THOMAS F. CROCKER, OF CHICAGO, ILLINOIS, ASSIGNOR TO RESERVE HOLDING COMPANY, OF CHICAGO, ILLINOIS, A CORPORATION OF DELAWARE

TELEPHONE SYSTEM

Application filed January 17, 1927. Serial No. 161,514.

The present invention relates to telephone systems in general, but is concerned more particularly with cord circuits and trunk circuits used in giving toll service and various auxiliary services to the subscribers of an automatic telephone exchange.

One feature of the invention relates to an arrangement involving the cord circuits at an operator's switchboard whereby the cord splitting keys, the dialing keys, the coin refund, and the coin collect keys are common to all the cord circuits of the position, thereby greatly simplifying the cord circuits and reducing the number of keys and associated connections required. A further feature of this arrangement is that the common apparatus is associated with a cord circuit responsive to the operation of the talking key individual to the cord, the common apparatus being otherwise not connected to or particularly associated with any one cord circuit.

According to a further feature of the invention, arrangements are made for automatically cutting out the inductive talking connections in the trunk circuits and for substituting metallic connections responsive to the operation of the operator's keys such as dialing and coin control, and ringing keys. It is an object of the invention to control this operation over the sleeve conductor and at the same time to permit the control of supervision in the cord circuit to be carried out over the sleeve conductor by the relays of the trunk circuits.

A further object of the invention is the production of a novel trunk circuit for use in connection with a so-called toll-service trunk extending to the switches of the toll train. This trunk circuit is so arranged that it is divided into two sections and inductively coupled by condensers of a capacity such that stray currents or ringing current applied at a distant point will not pass through in sufficient strength to start the signalling of the local subscribers in a manner to be hereinafter explained.

A further object of the invention is to produce a novel arrangement for use in connection with the cord circuit at the operator's switchboard whereby a simple loop dialing

circuit at the operator's switchboard may be used in conjunction with a toll line arranged for the so-called battery-loop impulsing, battery-loop impulsing being the term applied to an arrangement wherein the battery connections to the line are at the dialing end 55 rather than at the distant end of the line.

Other objects and features of the invention, having to do for the most part with the provision of arrangements for carrying the foregoing into effect, will become apparent upon a further perusal of the specification in connection with the accompanying drawings.

Referring now to the drawings comprising Figs. 1-4, Fig. 1 is a trunk diagram, and Figs. 2-4 show by means of the usual circuit diagrams so much of the apparatus in a telephone system embodying the features of the invention as is necessary to an understanding 65 of the invention.

General description

Referring now to Fig. 1, this drawing indicates a 10,000 line automatic telephone exchange inter-connected by toll lines such as TL¹ and TL² with two other distant exchanges (not shown). These jacks terminate at the toll board in the automatic exchange in the jacks J⁵ and J⁶, respectively. 75 The toll operator is provided with cord circuits, by means of which the toll lines TL¹ and TL² may be connected together, or either toll lines may be connected through automatic switches to any of the automatic subscribers. For the use of the automatic subscribers in setting up automatic-to-automatic connections, the so-called regular train of switches is provided, but when the toll operator sets up a connection she uses 80 a separate train of switches on account of the necessity for supervision, camp-on-busy, coin-control, and other features not required in the regular switch train. A train of toll switches includes a first selector such as the 85 first selector FS⁴, a transmission selector repeater (a second selector) such as TSR, and a connector such as C². One of the lines accessible to the connector C² is the line extending to the substation APS, an automatic 90 95 100

pay station #4300. It is assumed that the connector C, and the automatic pay station APS are similar to the connector H and the substation A, respectively, shown in Fig. 3 of the drawings in the Wicks Patent 1,633,149, granted June 21, 1927. It is assumed further that the transmission selector repeater TSR is similar to the selector repeater shown in Fig. 2 of the above-mentioned drawings and bearing the general reference characters R, E, and F, except that a release trunk conductor is added to the trunk line comprising conductors 70 and 71 of the above-mentioned drawings. This conductor is an extension of the conductors connected to armature 178 of the release relay 152, and it is necessary owing to the fact that the first selector FS⁴ is interposed between the transmission selector repeater TSR and the jack J⁸. FS⁴ is a standard two-wire selector.

The lineswitches LS¹—LS³ are assumed to be similar to the lineswitch C of the above-mentioned patent, being of the ordinary 25 rotary type.

It will be noted that a pay-station repeater PR has been inserted between the bank of the lineswitch LS³ and the first selector FS³. This pay-station repeater is used 30 primarily to collect or refund automatically a coin deposited at the pay station before a connection is attempted. It is assumed that the pay-station repeater PR and the first selector FS³ are similar to the pay-station repeater P and the first selector E in the drawings of the patent to Wicks No. 1,551,597, granted September 1, 1925.

It is assumed that there are a number of 40 manual pay stations in addition to the automatic pay-stations. The lines from the manual pay stations terminate in jacks such as the jack J¹ at the combined pay station and toll recording board. The calls between the manual pay stations and the automatic 45 substations are handled by the pay-station operator, who is provided with a number of trunk lines extending to lineswitches, such as the lineswitch LS¹, having access to regular first selectors.

50 The trunk lines from the tenth level of the regular first selectors extend to jacks such as the jack J⁸, at the combined pay-station and toll-recording board. The operator at this board makes out the usual tickets 55 concerning the desired connections and passes them over to the toll operator.

In order that the toll operator may set up 60 connections involving the manual pay-station lines, transfer trunks are provided extending between jacks, such as J⁷ and J⁴, at the two boards.

Referring now to Figs. 2-4, Fig. 2 shows 65 the pay-station and toll-recording board, including the cord circuit CC¹, the associated position equipment, the jacks J¹—J⁴, and the

line extending between the exchange and the manual pay station MPS. Fig. 3 shows the toll board, including the cord circuit CC², the jacks J⁵—J⁸, and it indicates also the position equipment assumed to be similar to the position equipment shown in Fig. 2. Fig. 4 shows the first selector FS¹ terminating the toll line TL².

Detailed description

The general description of the system and the equipment having been given, a detailed description of the operation will now be proceeded with.

For this purpose it will be assumed first 80 that a patron at the manual pay station MPS, Fig. 2, desires to converse with the subscriber at the automatic substation No. 4390, Fig. 1.

Call from pay station MPS to Automatic 85 Substation No. 4390.

When the receiver is removed at substation MPS, a circuit is closed over the associated line conductors for line relay 202 in the 90 exchange. Line relay 202 operates and closes a circuit at its upper armature for the line lamp 204. At its inner upper armature it closes a circuit for the visual signal 205, and its multiples in other positions. Upon noting the lighted condition of the lamp 204, the operator inserts the answering plug of an idle cord circuit, for example the answering plug of the cord circuit CC¹, into the jack J¹. When the plug has been fully inserted into 100 the jack, a circuit is completed over the sleeve of the plug and jack for the sleeve relay 203, including the upper spring contacts of the jack J¹, battery being connected in the cord circuit to the plug sleeve. Relay 203 105 operates and extinguishes the line lamp at its upper armature, at the same time closing a multiple circuit for the visual signal 205 and its multiples. At its inner armature, relay 203 disconnects relay 201, so as to prevent its operation at this time.

In the cord circuit, it will be noted that 115 battery is supplied to the sleeve of the answering plug through the resistance 211, through the resistance 213 and contacts on relays 214 and 215 and on the talking and ringing keys, and through the supervisory lamp 212 and contacts on the relays and keys mentioned. The resistance of the upper winding of relay 203 is of sufficient value to prevent the supervisory lamp 212 from becoming lighted at this time. The operator now throws her talking key, whereupon the sleeve conductor of the plug is disconnected from relay 214 and the supervisory lamp 212 120 and is transferred to the position equipment. The resistance 224 in the position equipment is sufficiently low to permit the marginal sleeve relay 203 to remain operated. As a further result of the throwing of the talking 125 key, the supervisory lamp 212 is lighted.

key, the talking strands of the cord circuit are connected to the talking conductors of the operator's head set through the contacts of the following keys: Collect answer, Refund answer, Cut-off answer, and Dial call.

The operator now converses with the subscriber and ascertains the destination of the desired connection. Upon learning that the subscriber desires to be connected with automatic substation No. 4390, the operator requests the subscriber to deposit a coin of the proper denomination. After she has heard the coin fall, the operator inserts the calling plug of the cord circuit into a jack, the jack J² for example, of a trunk line extending to a lineswitch. Upon the insertion of the plug into the jack J², a circuit is closed at the upper spring contacts of the jack J² for the upper winding of the relay 221, including the sleeve of the plug and jack. At its inner upper armature, relay 221 closes a circuit for the polarizing winding of the electro-polarized relay 222. This winding is composed of a relatively small number of turns of wire having a comparatively high resistance, and it alone cannot therefore operatively energize the relay. At its upper and lower armatures, relay 221 removes the shunt from around the talking condensers and it closes a bridge across the outgoing trunk conductors including impedance 223 and the upper winding of relay 222. The current flow in the upper winding of relay 222 now assists the current flow in the lower winding, with the result that the relay operates and connects the lower winding of relay 221 between the sleeve of the jack and ground, thereby lowering the resistance of the sleeve circuit sufficiently to cause the supervisory lamp 217 in the cord circuit to become lighted through the lower contacts of the ringing key. The lineswitch LS¹, Fig. 1, now operates and seizes, for example, the selector FS².

The operator now throws her Dial call key in her position equipment. At its inner contacts, this key disconnects the conductors between the talking key and the operator's head set, and at its upper contacts it closes a circuit through the lower contacts of the talking key for the cord splitting relay 216. Relay 216 operates and closes a connection between the talking conductors of the calling plug and the operator's head set by way of the keys to the right of the Dial call key, at the same time disconnecting the calling plug talking conductors from the right-hand repeating-coil windings. Relay 222, associated with the operator's head set, operates through the upper contacts of the Dial call key and shunts the associated condenser in the operator's talking conductors.

With the Dial call key operated, and with relay 216 operated, ground from the lower contacts of the Dial call key through contacts on relay 216 and on the ringing key is placed

on the calling plug, thereby shunting the sleeve relay 221 associated with the jack J². The lamp 217 continues to glow and relay 221 falls back, opening the bridge across the outgoing trunk conductors and opening the circuit of the polarizing winding of relay 222, at the same time shunting the talking condensers, thereby connecting the outgoing trunk conductors with the tip and ring conductors of the calling plug, which are now connected through the right-hand keys of the position equipment to the operator's head set. With the talking condenser in the head set shunted by relay 222, a holding bridge exists in the operator's head set including normally closed contacts on relay 223, the balancing resistance, secondary windings of the operator's induction coil, and the impulse springs of the calling device 221. The line relay of the seized first selector now remains operated through this bridge.

The operator now manipulates the calling device 221 in accordance with the digits in the called number 4390, with the result that the connection is extended from the seized first selector FS² to the line extending to substation 4390 through a second selector, the second selector SS, Fig. 1, for example, and a connector, the connector C¹ for example. Upon being operated, the connector C¹ applies ringing current to the called line in the usual manner.

After she has finished dialing the number the operator restores the Dial call key, thereby reconnecting the head set with the talking conductors of the cord circuit through the springs of the talking key, removing ground from the sleeve of the calling plug, and opening the circuit of relays 222 and 216. Relays 216 and 222 remain operated for an interval so as to hold the established connection until relay 221 associated with the jack J² has had time to reoperate and reestablish the holding circuit through relay 222 and impedance 223. The lamp 217 becomes extinguished momentarily pending the reestablishment of the bridge and the reoperation of relay 222, but it is relighted when relay 222 operates and closes the circuit through the lower winding of relay 221.

Having finished dialing the number, the operator now restores the talking key and turns to other duties. The restoration of the talking key at this time does not result in any relay operation, as it merely shifts the sleeve of the answering plug back to relay 214 and lamp 212 in addition to disconnecting the cord from the common talking circuit.

When the subscriber at the called substation responds to the ringing of his bell by removing his receiver, the connector C¹ reverses the connection between its incoming trunk conductors and its battery feed circuit, thereby causing a reversal of current flow in the circuit including relay 222, Fig. 2, asso-

iated with the jack J^2 . When this occurs, relay 222 falls back and disconnects the lower winding of relay 221 whereupon the lamp 217 becomes extinguished as it does receive sufficient current through the upper winding of relay 221 to remain lighted. When lamp 217 becomes extinguished, the operator is notified thereby that the called subscriber has answered.

10 The two subscribers may now converse with each other as desired, and when the conversation is terminated they both replace their receivers. When the receiver is replaced at the called substation, the connector 15 C^1 reverses its incoming-trunk-conductor connections back to normal, whereupon the polarized relay 222, Fig. 2, reoperates, causing the supervisory lamp 217 in the cord circuit CC^1 to become lighted again as a disconnect signal.

When the receiver is replaced at the manual pay-station MPS, line relay 202 falls back and closes a low resistance circuit between ground and the sleeve of the jack J^1 , which 25 circuit includes the lower winding of relay 203, normal contacts of relay 202, operated contacts of relay 203, and the upper springs of the jack J^1 . When this circuit is closed, the lamp 212 becomes lighted, thereby giving the operator a disconnect signal from the 30 calling station.

Upon perceiving the disconnect signal, the operator proceeds to take down the connection. Before doing so, however, she must 35 collect the coin deposited at the manual pay station MPS. In order to do this she reoperates her talking key so as to connect the talking conductors associated with the answering plug to her position equipment 40 through the left-hand keys thereof, after which she operates her Collect answer key. When this key is thrown, ground is placed on the sleeve of the answering plug through the lower contacts of the key, contacts of the 45 talking key, and contacts of the ringing key. This shunts the sleeve relay 203 in the trunk circuit associated with the jack J^1 , whereupon relay 203 falls back and closes a circuit for relay 201. Relay 201 operates and disconnects line relay 202, at the same time shunting the associated talking condensers 50 so as to give a clear circuit for the passage of the coin-collect current. At its remaining contacts, the Collect answer key disconnects the talking conductor from the operator's head set and connects them both to a 55 source of positive current of substantially 110 volts potential. This closes a circuit which may include both sides of the line in 60 case the receiver is off at the called substation, but which includes only the upper talking conductor at this time, as the receiver has been replaced. This circuit includes the 65 operating magnet at the pay station and this magnet is operated in the proper direc-

tion to collect the deposited coin. When the key is restored, the coin control magnet at the pay station restores and it is thereupon disconnected from the talking circuit in the usual manner.

In practice, the operator is usually provided with a supervisory relay in the coin control battery circuits so that she can reoperate the key a second time to ascertain whether or not the coin has been actually 75 collected, as the magnet will still be connected to the line if the coin has not fallen from the chamber.

When the operator restores the collect key, ground is removed from the sleeve of the answering plug, permitting relay 203 to pull up and open the circuit of relay 201, whereupon relay 201 falls back and reconnects the line relay. Following this, the operator restores her talking key and pulls down the 85 answering and calling plugs. When the answering plug is removed, relay 203 falls back and opens the circuit of the visual signal 205 and its multiples.

When the calling plug is removed, relay 90 221 falls back and opens the bridge across the associated trunk conductors and opens the circuit of the lower winding of the electro-polarized relay, whereupon relay 222 falls back and the connection through the automatic switches is released in the usual and well known manner. The entire connection is now released and the apparatus involved therein may be used to set up subsequent connection.

Call from pay station MPS completed over toll line TL^1

It will now be assumed that a patron at the manual pay station MPS desires to converse with a subscriber in the exchange to which the toll line TL^1 extends. Accordingly, the subscriber at substation MPS removes his receiver and gets into communication with the pay station and toll-recording operator, who makes a note of the particular calling line and of the line to which the connection is to be extended. This note is made on what is known as a ticket, and the ticket is given to the operator at the toll 115 board shown in Fig. 3.

When the operator at the toll board is ready to set up the connection, she inserts a plug of an idle cord circuit into the jack of a transfer trunk extending from the toll board to the pay-station board. In this instance it will be assumed that she inserts the calling plug of the cord circuit CC^2 into the jack J^7 . When this occurs, relay 305 operates through the sleeve of the plug and jack, but lamp 216 is not lighted owing to the relatively high resistance of relay 305. Relay 305 closes a circuit through contacts of relay 246 for the signal lamp 245 associated with the jack J^4 .

The operator at the pay-station board responds to the lighting of the lamp 245 by inserting the answering plug of an idle cord circuit, for example the answering plug of the cord circuit CC^1 , into the jack J^4 . When this occurs, relay 246 operates and extinguishes the lamp 245. The supervisory lamp 212 associated with the answering plug of the cord circuit CC^1 is not lighted at this time owing to the fact that ground potential has been removed from the sleeve of jack J^4 by the sleeve relay 305 of the jack J^7 .

The two operators now throw their respective talking keys and converse with each other in the usual manner. It may be pointed out of this time that the position equipment at the toll board is identical with the position equipment at the pay-station and toll-recording board, except that the branch conductor corresponding to the one used for operating relay 243 is omitted in the position equipment of Fig. 3. Whenever the operator at the toll board throws the talking key, the cord-splitting relay 314 operates and the two plugs of the cord are connected together through all the operators' common keys in series until the operator manipulates one of the common keys to separate the two plugs.

Upon learning that the toll operator is setting up the connection involving the manual pay station MPS, the pay-station operator inserts the calling plug of the cord circuit CC^1 into the jack J^4 so as to reserve the line and prevent it from being used in the ordinary manner until the toll call has been disposed of. When the plug is inserted, relay 203 operates and shunts its upper winding through a circuit path including its lower winding, the line relay 202 remaining normal. This results in a lighting circuit being closed for the supervisory lamp 217. The toll-recording and pay-station operator, however, does not signal the subscriber at the manual pay station for the time being, but she waits until she is requested to do so by the toll operator.

The toll operator now inserts the answering plug of the cord circuit CC^2 into the jack of an idle toll line, for example the toll line TL^1 . The busy or idle condition of the toll line is indicated by the condition of the visual busy signal 303. When the answering plug of the cord circuit CC^2 is inserted into the jack J^5 , a circuit is closed over the sleeve of the plug and jack for the cut-off relay 302, battery being supplied to the sleeve of the plug through the resistance 311, and through the resistance 318 and the lamp 315 by way of contacts of relays 312 and 313 and of the talking and ringing keys. Relay 302 disconnects the upper winding of the cut-off relay 301 and closes a circuit for the visual signal 303. The lamp 315 does not become lighted owing to the relatively high resistance of relay 302.

The operator now throws her ringing key

associated with the answering plug, thereby projecting ringing current out over the toll line TL^1 . It will be noted that the ringing key also opens a point in the sleeve circuit, leaving a battery connection to the sleeve circuit only through the resistance 311. This is for the purpose of dropping back the sleeve relay in those circuits containing marginal sleeve relays, but the sleeve relay 302 is sensitive and does not fall back at this time.

The operator at the toll board shown in Fig. 3, gets in touch with the distant operator after projecting ringing current over the toll line, and the distant operator extends the connection to the desired line in the usual manner. Assuming that the called line is idle and that the called subscriber responds, the originating toll operator then requests the called subscriber to wait a moment while she gets in touch with the calling subscriber. In order to do this, the originating toll operator has two courses open. She may withdraw and reinsert the calling plug of the cord circuit CC^2 a few times, with the result that each time she does so the disconnect lamp on the calling end of the cord circuit CC^1 is flashed by the placing of ground potential on the sleeve of the jack J^4 when the sleeve relay 305 falls back. As an alternative, the toll operator may ring over the transfer trunk by operating the ringing key associated with the calling end of the cord. This ringing key projects ringing current over the transfer trunk and in addition opens a connection in the sleeve circuit so that only the resistance 317 is left to supply battery to the sleeve. The sensitive sleeve relay 305 associated with the jack J^7 does not fall back when the ringing key is thrown.

In the cord circuit CC^1 , relay 215 responds to the ringing current repeated through the repeating coil windings and removes the shunt from around the winding of relay 214. Relay 214 it will be noted, has a copper collar, which copper collar is placed on the armature end of the relay core, as is indicated by the fact that a solid black symbol is used. The relay 214 is therefore slightly slow to operate so as to prevent the lamp 212 from being brought in in case a single stray impulse being received. However, when relay 215 vibrates several times in response to the ringing current, relay 214 has the short circuit removed from around it several times and the cumulative effect is that the relay operates and opens a further point in the short circuit, with the result that it remains operated after relay 215 has restored. At its upper armature, relay 214 disconnects the lamp 212 from the sleeve circuit and connects it to ground, whereupon the lamp 212 lights as a calling signal. If desired, ground through a suitable interrupting device instead of ground direct could be connected to one front contact of the upper armature of re-

lay 214 so as to give a distinctive signal to the operator to inform her that the lamp is lighted in response to the receipt of ringing current.

It may be that the ringing current continues over the established connection in sufficient strength to operate the ringer at the manual pay station MPS. This however, can not be depended on owing to the loss in the 10 trunk circuit associated with the jack J^1 , owing to the line-relay bridge and the series talking condensers.

Upon noting the lighted condition of the lamp 212, the pay-station and toll-recording 15 operator throws her talking key and converses with the toll operator. Relay 214 falls back and the lamp 212 is extinguished when the key is thrown. Upon being informed that the connection is now ready, the pay-station 20 and toll-recording operator throws her ringing key associated with the calling plug, now in the jack J^1 , whereupon ringing current is projected out over the line, and relay 203 falls back owing to the opening of the sleeve 25 connection at the ringing key, this relay being designed and adjusted so as not to hold up in series with the relatively high resistance 219. Upon falling back, relay 203 connects up relay 201, and this relay operates to 30 connect line relay 202 and by pass the talking condensers, this operation being similar to that performed when the Collect-answering key was thrown to collect the deposited coin as hereinbefore described. As the line 35 relay is now disconnected from in bridge of the conductors and as the talking condensers are by-passed, the ringing current has a clear path to the manual pay station. When the ringing key is restored, relay 203 reoperates and disconnects relay 201 whereupon the latter relay falls back.

When the call is answered at the manual pay station, the pay-station operator is notified of the answered condition by the extinguishing of the calling supervisory lamp 217. The operator now throws her calling key and she throws her answering Cut-off answer key temporarily so as to prevent the distant subscriber from hearing her conversation with the patron at the manual pay station. The operator requests the pay-station patron to deposit coins of the correct number and value, being informed that he does so by the usual arrangement of gongs which 50 are located in close proximity to the transmitter. After the coins have been deposited, the operator throws her Collect call key, whereupon the positive 110 volt source of current is connected to both sides of the talking circuit extending through the calling plug to the jack J^1 , and a ground potential is placed on the sleeve of the calling plug, short circuiting relay 203, which falls back and operates relay 201 to complete the collect circuit. When the operator restores the collect

key the circuits are restored, after which the operator may restore her Cut-off answer key and inform the toll operator that the calling subscriber is ready to converse. The toll operator repeats this order to the subscribers and they proceed with the conversation.

When the conversation is over, the two subscribers replace their receivers. When the receiver is replaced at the manual pay station, line relay 202 falls back and closes a low resistance circuit between ground and the sleeve of the jack J^1 including the lower winding of relay 203. When this occurs, the calling supervisory lamp 217 becomes lighted through the plug of the cord to give the operator a disconnect signal. When the operator receives this disconnect signal, she throws her talking key and inquires whether the connection may be taken down. Assuming that the pay-station operator gets no reply, she throws the ringing key on the answering end of her cord, thereby projecting ringing current over the transfer trunk to the cord circuit CC^2 and also through the cord circuit CC^2 to the distant toll board. Relay 313 in the cord circuit CC^2 responds to the ringing current and causes the operation of relay 312 which opens a further point in the previous shunt around its winding so that it remains operated after relay 313 has restored. Both toll operators throw their talking keys and the three operators converse with each other to be sure that the connection is not pulled down prematurely.

Upon ascertaining that the conversation is completed, the operators pull down the connection and restore their talking keys, whereupon the apparatus reverts to the position shown in the drawings.

Call from substation APS completed over toll line TL²

It will now be assumed that a patron at the automatic pay station APS, No. 4300, in Fig. 1, desires to converse with a subscriber in the exchange reached by way of the automatic toll line TL^2 . In this case the calling pay-station patron removes his receiver, whereupon the lineswitch LS^3 operates to select an idle first selector, for example the first selector FS^3 . When the calling device is operated in accordance with the digit 0 assigned to the toll recording operator, the first selector FS^3 raises its wipers opposite the tenth level and selects an idle trunk line, for example the trunk line extending to the jack J^3 , shown in detail in Fig. 2. When this trunk line is seized, line relay 244 operates over the calling line and closes a circuit for release relay 243 and a multiple circuit for the lamp 241. Relay 243 operates and grounds the associated release trunk conductor at its upper armature so as to afford a holding circuit for the operated selector, and at its lower armature closes a connection between the associated

source of ringing current and the lower trunk conductor. This connection includes a condenser of a relatively small capacity with the result that a slight tone is placed on the talking circuit so as to inform the calling pay-station patron that the toll recording operator is being signalled. This source of ringing current is usually the regular interrupted source used in connection with the connector switches to signal called lines.

When the toll recording operator notes the lighted condition of the lamp 241, she inserts the answering plug of an idle cord circuit, for example the answering plug of the cord circuit CC^1 into the jack J^s . When this occurs, a circuit is closed at the upper spring-contacts of the jack J^s for relay 242, whereupon relay 242 operates and locks itself in multiple with release relay 243, at the same time extinguishing the lamp 241 and disconnecting the tone source from the line.

The toll recording operator now throws her talking key and converses with the calling pay-station patron, making out the usual ticket regarding the desired connection. When this has been done, the receiver is replaced at the pay station, whereupon the relay 244 falls back. The plug may be withdrawn from the jack J^s either before or after

this takes place. Assuming the plug is withdrawn before the pay-station patron hangs up, the original energizing circuit of relay 242 is opened at the upper springs of the jack J^s , but relay 242 remains operated in multiple with relay 243. Then, when line relay 244 falls back, relays 242 and 243 both fall back, restoring the circuits to normal.

In case the pay-station patron hangs up before the operator removes the plug from the jack, relay 244 falls back, but relay 243 remains operated in parallel with relay 242, and the answering supervisory lamp becomes lighted over the sleeve of the jack J^s and the sleeve of the answering plug owing to the placing of a ground potential on the sleeve of the jack by relay 244. When the operator perceives this disconnect signal she removes the plug from the jack.

The connection would ordinarily be set up by the toll operator upon the receipt of the ticket calling for the connection, and a cord circuit such as the cord circuit CC^2 would be used. However, in order to explain how the pay-station and toll-recording operator may help out the toll operator when the necessity rises, it will be assumed that the pay-station operator handles the connection just recorded owing to a peak demand for toll connections. The two operators' positions are located side by side and the pay-station and toll-recording operator may reach over into the toll position with her own plugs and set up connections through the toll board with the pay-station cords.

In this case, the pay-station operator in-

serts the calling plug of an idle cord circuit into the jack of an idle toll service trunk, for example the calling plug of the cord circuit CC^1 into the jack J^s . When this occurs, sleeve relay 324 operates over the sleeve of the plug and jack and through the upper springs of the jack, the ground potential being supplied to the upper terminal of the relay only after the plug is fully inserted so as to prevent possible preliminary impulses due to careless or hesitant insertions of the plugs into the jack. Relay 324 closes a bridge across the outgoing trunk conductors including relay 325 and the impedance winding 327. Relay 325 operates in this bridge and connects relay 326 in multiple with the upper winding of relay 324. Relay 326 operates and shunts its upper winding. Relay 326 is provided with a relatively high resistance upper winding so as to enable it to operate quickly, and this winding is shunted so as to permit the calling supervisory lamp in the cord circuit to become lighted at this time through the lower windings of relays 324 and 326. Relay 326 also removes the shunt from around the associated condensers.

Responsive to the closure of the bridge across the trunk conductors outgoing from the jack J^s , the first selector FS^1 is prepared for operation in the usual manner.

The pay-station operator throws her talking key in the cord circuit CC^1 , after which she throws her Dial call key, resulting in the operation of the cord splitting relay 216 and in the placing of ground on the sleeve of the plug through contacts of the Dial call key and contacts of relay 216. When this occurs, relays 324 and 326 associated with the jack J^s both fall back, but relay 326 falls back sooner than relay 324 owing to its marginal adjustment. Relay 324 opens the bridge, but, prior to that, the bridge is re-established around the condensers associated with relay 326, and including the right-hand keys at the operator's position equipment and the operator's head set conductors, relay 222 having been operated in the manner previously pointed out by the upper contacts of the Dial call key to shunt the associated condenser. The operator now manipulates her calling device in accordance with the digits in the number of the calling pay station, whereupon the connection is set up to the pay station through the toll train and may include, in addition to the first selector FS^1 , the transmission selector repeater TSR and the connector C^2 . The connector is arranged so that it does not start to apply ringing current upon being operated, but the pay-station line is made busy to the other connectors having access to it so that the line will be available when needed.

The pay-station operator now inserts the answering plug of the cord circuit CC^1 into

the jack associated with an idle toll line in the group to which the toll line TL^2 belongs, the toll line jack J^e for example. When this occurs, relay 411 operates through its upper winding, and through the sleeve of the jack and plug, disconnecting the lower winding of the ring-up relay 412 from across the associated talking conductors, and connecting the talking conductors 403 and 404 of the jack J^e with the corresponding conductors associated with the right-hand repeating-coil windings, at the same time removing the dialing connections from conductors 403 and 404. As a further result of the insertion of the plug into the jack, a circuit is closed at the upper jack contact including the resistance 322 and relay 414 of the first selector FS^1 . Relay 414 operates and at its inner upper armature places ground on release trunk conductor 406, thereby operating the visual signal 323 and its multiples. At its upper and lower armatures, relay 414 disconnects the impulse conductors of the toll line TL^2 from the incoming impulse relay 415 and connects them instead to ground and to battery respectively, the lower conductor being grounded directly at the lower armature of relay 414, and the upper conductor being connected to battery through the middle upper armature of relay 411 and the resistance 413. The distant impulse receiving relay, corresponding to relay 415, Fig. 4, operates and prepares the associated selector corresponding to the selector FS^1 for operation in the usual manner.

The pay-station operator (now acting as the toll operator) has two courses open to her she may ring out over the toll line TL^2 and have the distant operator set up the connection in any way she sees fit or she may dial the connection up through the distant automatic switches in case the called line is an automatic line. It will be assumed in the present case that she does the latter. In order to do this, the operator throws her talking key associated with the cord circuit CC^1 , Fig. 2, after which she throws her Dial answer key, resulting in the operation of the relays 222 and 216 in the manner hereinbefore pointed out and in the placing of ground on the sleeve of the answering plug through operated springs of the talking key and normal springs of the ringing key. When this is done, the cut-off relay 411, Fig. 4, falls back because its upper winding is shunted. At its middle upper armature it opens the connection through which battery was initially supplied to the upper limb of the toll line TL^1 , at the same time connecting up the dialing branches of the conductors 403 and 404, conductor 403 being connected to battery through resistance 413 and conductor 404 being connected to the upper limb of the toll line TL^2 through the working contact and upper armature of relay 414. It will be noted that the effect of this is that the bridge including

the operator's head set and dialing equipment shown in Fig. 2 is inserted into the battery feed to the upper limb of the toll line across the gap opened at the middle upper armature of relay 411. It may be pointed out, of course, that the contacts of relay 411 are so adjusted that this change is made without a momentary loss of current through the toll line.

As the loop circuit over the toll line TL^2 now includes the impulse springs of the calling device 221, Fig. 2, the operator may now dial the number of the distant subscriber, whereupon the distant relay corresponding to relay 415, Fig. 4, responds with the result that the connection is set up to the desired line. The operator may, of course, restore her dial answering key as soon as she has finished dialing, whereupon relay 411 operates again shifting the battery supply circuit of the toll line back to its original path through the middle upper armature of relay 411.

Assuming that the desired line is idle and that the called subscriber responds, the pay-station operator requests him to wait a moment while she signals the calling subscriber. In order to signal the calling subscriber, the pay-station operator throws the ringing key of the calling end of her cord circuit CC^1 , whereupon the lamp 217 is extinguished and the marginal relay 326, Fig. 3, falls back owing to the disconnection of the supervisory lamp 217 from the plug of the cord, but the sensitive relay 324 remains operated so as to maintain the bridge including relay 325 and impedance 327 closed. When relay 326 falls back it shunts the associated condensers so as to permit sufficient ringing current to pass through to result in the calling line being signalled. These condensers are of small capacity so that in case a distant operator should ring over a toll line when this trunk is connected with the toll line the condensers will block the ringing current so as to prevent the premature signalling of the originating subscriber. When the operator restores her ringing key, relay 326 reoperates and the lamp 217 relights. The connector C^2 responds to the ringing current and signals the pay station intermittently in the usual manner.

When the pay-station patron responds to his recall, the current flow over the trunk conductors outgoing from the jack J^s is stopped in the transmission selector repeater TSR , Fig. 1, in a manner explained in the application hereinbefore referred to. When this occurs, relay 325 falls back and disconnects relay 326, whereupon the lamp 217 becomes extinguished owing to the fact that it cannot glow in series with both windings of relay 324. The operator now requests the pay-station patron to deposit the proper coins, which are collected upon a momentary operation of the Collect call key and in a man-

ner simliar to that described hereinbefore in connection with the call from the manual pay station MPS. It may be pointed out that relay 216 in the cord is operated, and that relay 324 restores responsive to the placing of a ground potential on the plug sleeve. 5

After the collecting operation, the two subscribers may converse with each other in the usual manner.

10 When the conversation is terminated, the two subscribers replace their receivers. When the receiver is replaced at the pay station, the current flow over the trunk conductors outgoing from the jack J^s is reestablished, whereupon relay 325 reoperates and connects 15 relay 326 in multiple with the upper winding of relay 324. When this occurs relay 326 shunts its own upper winding and the lamp 217 lights again as a disconnect signal.

20 Upon perceiving the disconnect signal, the operator listens in to make sure that the conversation is over, and upon finding it is she pulls down the connection. This results in the release of the automatic switches and in 25 the restoration of the other circuits to their normal conditions.

Call over toll line TL^2 to line No. 4390

It will now be assumed that the operator 30 in the exchange to which the toll line TL^2 extends receives a ticket calling for connection to be set up to line No. 4390, Fig. 1. When the distant operator is ready to set up this connection, she makes a connection with 35 the toll line TL^2 through a jack similar to the jack J^e , Fig. 3, whereupon a source of current is placed across the two conductors of the toll line TL^2 at the originating end in the manner hereinbefore explained in connection with the first selector FS^1 . When 40 this occurs, the bridged relay 415 in the first selector FS^1 operates and closes a circuit for release relay 416. Release relay 416 grounds the release trunk conductor 406 at its upper 45 armature, at the same time opening a point in the circuit of release magnet 420 and in the circuit of relay 414. At its lower armature, relay 416 prepares a circuit for vertical magnet 421. Signal 323 and its multiples become 50 operated over conductor 406 to indicate the busy condition of the trunk line.

When the calling operator dials the first digit 4 in the desired number, relay 415 falls back four times. Each time it does so it 55 closes a circuit for vertical magnet 421 through the series relay 417. Relay 417 operates when the first impulse of current is delivered, and, being slow acting, it remains operated until the last impulse is received. 60 Upon operating, relay 417 prepares a circuit, which is closed when the switch moves off normal, from the grounded release trunk conductor 406 (now grounded at the upper armature of relay 416) for relay 418 through 65 the associated off-normal contacts. Relay

418 operates upon the closure of this circuit and closes at its upper armature a locking circuit for itself including the interrupter contacts of rotary magnet 422. At its lower armature, relay 418 prepares a circuit for 70 magnet 422.

It usually happens that ring up relay 412 operates responsive to the first interruption in the line current, due to the self induction of relay 415. Relay 412 closes its locking 75 circuit in the usual manner, but it is disconnected and falls back right away due to the operation of relay 411 through its lower winding by off-normal contacts of the selector. The local toll operator is therefore not 80 signalled.

When series relay 417 falls back at the end of the digit, it closes a circuit for rotary magnet 422 including the grounded release trunk conductor 406, whereupon magnet 422 85 operates and rotates the wipers 431-433 one step. Near the end of its stroke, magnet 422 opens the circuit of stepping relay 418, whereupon relay 418 falls back and opens the circuit of rotary magnet 422. Magnet 422 falls 90 back and closes its interrupter contacts again.

The further operation depends upon whether the trunk line is busy or idle. If this trunk line is idle, it is immediately seized by the selector in a manner to be hereinafter 95 explained. If the trunk line is busy, however, a circuit is closed upon the falling back of the rotary magnet for reoperating relay 418 through the resting contact and inner upper armature of relay 419 and test wiper 432. 100 When relay 418 reoperates, magnet 422 is re-operated, whereupon the wipers are advanced another step. This alternate operation continues in the usual manner until an idle line is reached, which trunk line, it will be assumed, is the one comprising conductors 105 434-436 and extending to the second selector SS. When this idle trunk line is reached, relay 419, having been short circuited previously by the ground potential encountered 110 by test wiper 432, being no longer short circuited, now operates from ground on the release trunk conductor 406 and in series with stepping relay 418 and the associated off-normal and interrupter contacts. Upon operating, relay 419 opens a point in the vertical magnet circuit at its inner lower armature; opens a further point in the test circuit and grounds test wipers 432 at its inner upper armature so as to make the seized trunk busy 115 immediately; and at its upper and lower armatures connects up the wipers 431 and 433. When the wipers are connected up, the line relay (not shown) of the second selector SS, Fig. 1, operates over conductors 434 and 436, 120 wipers 431 and 433, upper and lower armatures of relay 419, left-hand repeating-coil windings, and the lower armature of relay 415. The second selector SS is thereby prepared for operation in the usual manner.

When the calling operator dials the next digit 3 in the desired number, relay 415 of the first selector SS¹ falls back three times. Each time it does so it opens the bridge across the wipers 431 and 433, with the result that the wipers of the second selector SS, Fig. 1, are raised opposite the third level in the usual manner, whereupon the selector proceeds to select an idle trunk. It may be assumed that the trunk selected is the one extending to the connector C¹.

Responsive to the dialing of the last two digits, 9 and 0, the connector C¹ raises its wipers opposite the ninth level and then rotates them into engagement with the tenth set of bank contacts in that level and automatically applies ringing current to the line of substation No. 4390.

When the called subscriber responds to the ringing of his bell by removing his receiver, the toll operator at the distant exchange is able to converse with him, and she instructs him to wait on the line while she completes the connection.

The connection may be completed in the distant office in any well known or desired manner.

When the connection is pulled down by the distant operator, relay 415 falls back and opens the circuit of release relay 416 at its inner armature, and at its lower armature opens the bridge across the line wipers, with the result that the second selector SS and the connector C¹ release in the usual manner. The release of the first selector S¹ is effected by magnet 420 upon the falling back of release relay 416, the release circuit including the associated off-normal contacts, which open as soon as the normal position is attained.

All trunks busy at the first selector FS¹

Assuming now that the first selector is operated and, upon rotating, finds all trunks in the selected level busy, the rotation continues until the wipers 431—433 pass beyond the last set of bank contacts upon the eleventh rotary set. When this occurs the cam 423 operates the associated eleventh rotary step contacts. Relay 419 operates at this time just as though an idle trunk were found, but its operation is of no particular utility. The eleventh rotary step contacts connect a source of busy signalling current across the talking conductors so as to inform the calling operator of the busy condition. The selector releases in the above described manner when the operator in the distant exchange pulls down the connection.

Call from the toll line TL² to the toll line TL¹

Assuming now that the operator in the exchange to which the distant end of the toll line TL² is extended takes the toll line TL² for use to complete a connection through the

toll board shown in Fig. 3 to the exchange to which the toll line TL¹ extends, the selector FS¹ is prepared for operation in the usual manner. Instead of dialing, however, the calling toll operator projects ringing current out over the toll line TL², whereupon relay 412, whose lower winding is bridged across the right-hand repeating-coil winding in series with a condenser, responds to the ringing current repeated through the repeating-coil windings. Upon operating, relay 412 closes a locking circuit for its upper winding at its upper armature, and at its lower armature grounds conductor 401, lighting the call lamp 321, Fig. 3. When the toll operator notes the lighted condition of the lamp 321, she inserts the answering plug of an idle cord circuit, for example the answering plug of the cord circuit CC², into the jack J⁶. When this occurs, a circuit is completed over the sleeve of the plug and the sleeve of the jack for cut-off relay 411. Relay 411 operates and unlocks relay 412. At the same time it disconnects the lower winding of relay 412 from in bridge of the talking conductors; connects said conductors with the branch leading to the jack; and disconnects said branch from the dialing conductors. Relay 414, it will be noted, is not operated at this time owing to the fact that its circuit is open at the upper armature of release relay 416.

The operator at the cord circuit CC² now throws her talking key and converses with the calling operator. Upon ascertaining the destination of the call, the toll operator inserts the calling plug of the cord circuit CC² into the jack of an idle toll line leading to the desired exchange, for example the jack J⁵ of the toll line TL¹. When this is done relay 302 operates over the sleeve circuit and disconnects the upper winding of relay 301, at the same time closing a circuit for the visual signal 303 and its multiples. The operator now throws the ringing key associated with the calling end of the cord circuit CC², thereby projecting ringing current out over the toll line TL¹. Relay 302 does not fall back at this time, as it is designed so as to remain operated in series with the resistance 317.

When the connection set up between the toll line TL¹ and TL² is to be taken down, the operator at the cord circuit CC² is informed of this fact upon the receipt of ringing current over the toll line TL², which ringing current operates the ringing response relay 313. Relay 313 removes the shunt from around relay 312, whereupon relay 312 operates and opens a further point in its previously-existing shunt, and at its lower armature closes a circuit for the disconnect lamp 315. The operator at the cord circuit CC² reoperates her talking key, and, when

told to do so, takes down the connection, whereupon relay 411 restores.

When the distant operator pulls down her cord, relays 415 and 416 fall back and ground is removed from conductor 406, restoring the visual signals at the toll-board positions.

When an automatic subscriber desires to call to a manual pay station, he dials the digit 0, whereupon the connection is extended to the pay-station and toll-recording board in the manner previously explained. The operator responds and completes the connection through a cord circuit such as the cord circuit CC¹, Fig. 2.

It will be noted that the usual monitoring key is shown in connection with the cord circuit CC¹. This monitoring key is used in case the operator desires to listen on a connection to discover whether or not the subscribers are having any difficulty in understanding each other, and it is arranged to increase the impedance of the operator's head set by operating relay 223 to place the receiver in series with both secondary windings of the operator's induction coil. A similar key is provided at the cord circuit CC².

What is claimed is:

1. In a telephone system, an operator's switchboard, link circuits at said switchboard, a position equipment at said switchboard arranged to supplement any link circuit and including talking conductors having manually operable keys connected therein, a repeating coil in each link circuit dividing the talking conductors thereof into two inductively coupled sections, means including a manually operable key individual to each link circuit for connecting one section of the talking conductors thereof to said position equipment, a relay individual to each link circuit and arranged to connect the other section of the talking conductors thereof to said position equipment, and an operating circuit for any one of said relays including contacts of one of the manually operable keys in the position equipment and contacts of the said manually operable key in the same link circuit.

2. In a telephone system, an operator's switchboard, link circuits at said switchboard, a position equipment at said switchboard including talking conductors having manually operable keys connected therein, a talking key for each link circuit, and connections controlled jointly by any operated one of said talking keys and one of the common keys for associating said position equipment with whichever one of said link circuits contains the operated talking key.

3. In a telephone system, operator's link circuits, means for splitting any link circuit into two sections, connections common to said link circuits for bridging the gap between the two sections of any split link circuit, an operator's calling device associated with said

common connections, and means for opening the common connection between said calling device and either section of said link circuit.

4. In a telephone system, an operator's link circuit, means for splitting said link circuit into two sections, circuit connections common to said link circuit and to other similar link circuits for bridging the gap between the two sections, a calling device connected in circuit with the operator's head set, circuit connections between the calling device and the operator's head set and said common equipment, and means in said common equipment for opening the connection between the calling device and the operator's head set and either section of the connected link circuit.

5. In a telephone system in which connections through automatic switches are set up through an operator's switchboard, link circuits at said switchboard through which said connections are extended, a calling device common to said link circuits for controlling the automatic switches, means individual to each link circuit for connecting said calling device to both ends of such link circuit, and means common to said link circuits for disconnecting said calling device from either end of a link circuit in use while leaving it connected to the other end of such link circuit.

6. In a telephone system in which connections including pay stations are set up through an operator's switchboard, link circuits at said switchboard through which said connections are extended, a position equipment at said switchboard common to all said link circuits, means individual to each link circuit for associating the link circuit with said position equipment, and means in the position equipment for disposing of coins deposited at said pay stations.

7. In a telephone system, an operator's switchboard, link circuits thereat for setting up talking paths between telephone lines, each link circuit comprising two sections, means including a talking key and a relay individual to each link circuit for dividing the link circuit into its two sections, circuit connections common to all said link circuits and controlled by said key and relay for bypassing the open point in any link circuit, and a circuit for said relay extending thereto from said common equipment through contacts of said key.

8. In a telephone system, an operator's switchboard, link circuits at said switchboard including talking conductors, means for dividing any link circuit into two sections, an impulse-sending calling device, means for completing a connection from the operator's head set and the calling device to one section of a divided link and for completing a separate connection from said operator's head set and the calling device to the other section of such link, a control key

in one connection common to all the link circuits, and another control key in the other connection common to all said link circuits.

9. In a telephone system, an operator's switchboard, automatic switching apparatus, a plurality of link circuits at said switchboard for use in completing telephone connections via said automatic switching apparatus, a talking key individual to each link circuit, circuit arrangements such that when the talking key is thrown a connection is established from the corresponding link circuit to the operator's head set and calling device, each link circuit comprising two normally connected sections, and means common to all the link circuits for enabling the operator to connect her head set and calling device with either section of a link circuit at which the talking key is thrown to the exclusion of the other section of such link circuit.
10. In an operator's link circuit, a supervisory lamp arranged to be lighted or not under the control of current flow over the sleeve conductor of the link circuit, a ringing current responsive device in said link circuit, and means for lighting said lamp when the said device responds to ringing current regardless of any flow of current over the sleeve circuit.

11. In a telephone system, a plug ending operator's link circuit, a supervisory lamp connected to the sleeve of said plug, and means in said link circuit responsive to the receipt of ringing current for disconnecting said lamp from said sleeve and for closing a lighting circuit for the said lamp.

12. In an operator's switchboard, a link circuit terminating in a plug, a cooperating jack, a supervisory lamp connected to the sleeve of the plug, a holding relay connected to the sleeve of said jack, a supervisory relay associated with said jack, circuit arrangements controlled by said supervisory relay for regulating the current flow over the sleeve of the plug and jack to control the lighting of the said lamp, and circuit arrangements associated with said plug for regulating the current flow over said sleeve to control said holding relay.

13. In a telephone system, an operator's switchboard, a link circuit at said switchboard terminating in a plug, a cooperating jack, a supervisory circuit including the sleeve of the plug and jack, a supervisory relay associated with said jack and arranged to be controlled over the talking conductors extending from the spring contacts thereof, circuit arrangements whereby the current flow over the sleeve circuit is controlled in accordance with the normal or operated state of said supervisory relay, and means associated with said plug for controlling said supervisory relay over said sleeve circuit.

14. In a telephone system, an operator's

switchboard, a jack at said switchboard, a line extending from said jack divided into two inductively coupled sections, a plug-ending link at said switchboard, and means in said line controlled over the sleeve of the plug and jack for by-passing or including the inductive coupling in the connection of said line at the will of the operator at the switchboard.

15. In a telephone system, a manual switchboard, an automatic switchboard, a trunk line extending from a jack at the manual switchboard to said automatic switchboard, said trunk line being divided into two inductively coupled sections, a switch-holding path connected to the automatic-switchboard section of said trunk line, a calling device at said manual switchboard for controlling the switches in the automatic switchboard, a plug for associating said calling device with said trunk line through said jack, and means under control of the operator for by-passing the inductive connections between the two sections of the trunk line and for removing the switch-holding connection from the second section of the trunk line so as to place the mechanism at the automatic switchboard under the control of said calling device.

16. In a telephone system, a manual switchboard, an automatic switchboard, a trunk line extending from a jack at the manual switchboard to said automatic switchboard, said trunk line being divided into two inductively coupled sections, a switch-holding path connected to the automatic-switchboard section of said trunk line, a calling device at said switchboard, a plug for associating said calling device with said trunk line through said jack, and means controlled over the sleeve of the plug and jack under the control of the operator for by-passing the inductive connections between the two sections of the trunk line and for removing the switch-holding connection from the second section of the trunk line so as to place the mechanism at the automatic switchboard under the control of said calling device.

17. In a telephone system, a manual switchboard, an automatic switchboard, a trunk line comprising two inductively coupled sections extending from said manual switchboard to said automatic switchboard, means for setting up a connection through said automatic switchboard controlled from the manual switchboard, the inductive connection between the two sections being of such a value as to bar the passage of ringing current, and means responsive to the operation of a ringing key at the manual switchboard for enabling ringing current to pass over the two sections.

18. In a telephone system, a manual switchboard, an automatic switchboard, a trunk line comprising two inductively coupled sections extending from said manual switchboard to said automatic switchboard, means for setting

- up a connection through said automatic switchboard controlled from the manual switchboard, the inductive connection between the two sections being of such a value 5 as to bar the passage of ringing current, means automatically responsive subsequent to the completion of the above connection for by-passing said inductive connections to facilitate the flow of talking current, and means 10 responsive to the operation of a ringing key at the manual switchboard for enabling ringing current to pass over the two sections.
19. In a telephone system, a manual switchboard, an automatic switchboard, a trunk line 15 extending from a jack at the manual switchboard to the automatic switchboard, said trunk line comprising two inductively coupled sections, a calling device at the manual switchboard, a control circuit for the 20 switches at the automatic switchboard including the two conductors of the second section of the trunk line in series, and means for placing the calling device in series with one side of the second trunk-line section over a 25 circuit path including the two sides of the first section of the trunk line in series.
20. In a telephone system, an operator's switchboard, link circuits at said switchboard, each including a pair of talking conductors and an auxiliary conductor, lines terminating at said switchboard having corresponding conductors, operator-controlled means for connecting the 30 said conductors of any one of said link circuits with the corresponding conductors of any one of said lines, a position equipment at said switchboard arranged to supplement any link circuit and including conductors corresponding, respectively, to the said 35 conductors of said link circuits, means for connecting the said conductors of any link circuit with the corresponding conductors of said position equipment, a plurality of operator's keys in each link circuit, and a plurality of operator's keys in said position equipment.
21. In a telephone system, an operator's switchboard, link circuits at said switchboard, each including a pair of talking conductors and an auxiliary conductor, lines terminating at said switchboard having corresponding conductors, operator-controlled means for connecting the 40 said conductors of any one of said link circuits with the corresponding conductors of any one of said lines, a position equipment at said switchboard arranged to supplement any link circuit and including conductors corresponding, respectively, to the said 45 conductors of said link circuits, means for connecting the said conductors of any link circuit with the corresponding conductors of said position equipment, means operable at the will of the operator at said position for exercising control over the said conductors
- of said link circuit through the medium of said conductors of said position equipment, and means in each link circuit for sending ringing current out through either end thereof of independent of said position equipment. 70
22. In a telephone system, an operator's switchboard, link circuits at said switchboard each including a pair of talking conductors and an auxiliary conductor, a repeating coil in each link circuit dividing the talking conductors into two inductively coupled sections, lines terminating at said switchboard having corresponding conductors, operator-controlled means for connecting the said conductors of any one of said link circuits with the corresponding conductors of any one of said lines, a position equipment at said switchboard arranged to supplement any link circuit and including conductors corresponding, respectively, to the said conductors on any one of said link circuits, means for connecting the said conductors of any link circuit with the corresponding conductors of said position equipment, and means operable at the will of the operator at said position for exercising a control over the connected link circuit through the medium of her position equipment. 80
23. In a telephone system, an operator's switchboard, link circuits at said switchboard each including a pair of talking conductors and an auxiliary conductor, lines terminating at said switchboard having corresponding conductors and having coin-controlled equipment connected thereto, operator-controlled means for connecting the said conductors of said link circuit with the corresponding conductors of any one of said lines, a position equipment at said switchboard arranged to supplement any link circuit and including conductors corresponding, respectively, to the said conductors of any one of said link circuits, means for connecting the said conductors of any link circuit with the corresponding conductors of said position equipment, means including manually operable keys in said position equipment for exercising either of two controls over the said conductors of a line through a connected link circuit via said position equipment, and means responsive to said controls to collect and refund coins, respectively, at said coin-controlled apparatus. 90
24. In a combined manual and automatic telephone system, an operator's switchboard, link circuits at said switchboard, a talking key for each link circuit, a calling device at said switchboard common to all said link circuits, operator-controlled contacts individual to said calling device but forming no part thereof and being operable separate therefrom, and means responsive to an operation of said contacts for operatively associating said calling device with whichever link circuit contains an operated talking key. 100
25. In a combined manual and automatic 110

- telephone system, a plurality of link circuits each comprising two sections, a calling device, a manually operable key for each link circuit for determining with which link circuit the calling device is to be associated, means common to all link circuits and controlled by the operator for determining with which section of the link circuit the calling device is to be associated, means included in said connecting means for directly connecting the calling device with one section of a predetermined link circuit, and means including means individual to each link circuit and part of said common means for connecting the calling device to the other section of a link circuit.
26. In a telephone system, an operator's switchboard, link circuits over which talking connections are to be set up, a position equipment at said switchboard arranged to supplement any link circuits in a plurality of ways, means for associating said position equipment with a link circuit and for operating the position equipment to supplement the associated link circuit in exercising any desired one of a plurality of controls over the connection extending through the link circuit, and means individual to each link circuit for projecting ringing current out over any connected line.
30. In witness whereof, I hereunto subscribe my name this 12th day of January, A. D., 1927.

THOMAS F. CROCKER.
